UNITED STATES PATENT OFFICE.

FRANCIS M. BOOKWALTER, OF SPRINGFIELD, OHIO, ASSIGNOR TO THE JAMES LEFFEL & COMPANY, OF SAME PLACE.

WATER-WHEEL.

SPECIFICATION forming part of Letters Patent No. 465,813, dated December 22, 1891.

Application filed April 16, 1891. Serial No. 389,130. (No model.)

To all whom it may concern:

Be it known that I, FRANCIS M. BOOKWALTER, a citizen of the United States, residing at Springfield, in the county of Clark and State of Ohio, have invented certain new and useful Improvements in Water-Wheels, of which the following is a specification, reference being had therein to the accompanying drawings.

10 My invention relates to certain new and useful improvements in water-wheels.

The objects of my improvements are to provide means to operatively connect a series of gates so as to actuate each of said gates simultaneously through said connection, to exert the operative force for adjusting the gates at a point practically midway between the length of the gates and preferably at substantially diametrically-opposite points of a 15 connecting-ring at each end of the gates, and to multiply the force exerted thereon by a suitable mechanism. With these objects in view my improvements have reference to rotatably-mounted rings and a cross connection 20 for the same adapted to be operated from outside of the case, have reference to a forked rod forming said cross connection, have reference to mounting a pair of operating-rods at substantially diametrically-opposite points 25 on said rings, have reference to a lever mechanism to operatively connect said rods and multiply the power transmitted to the gates, and have reference to points of detail herein- 30 after described and claimed.

35 In the accompanying drawings, forming a part of this specification, and on which like reference-letters indicate corresponding parts, Figure 1 represents a side view of a wheel proper and its adjacent parts, portions being 40 broken away to show the gates and the casing in section; Fig. 2, an edge view of a wheel proper and its adjacent parts, the casing being broken away; Fig. 3, a similar view to Fig. 1, showing one form of operating means and 45 forked rods forming the cross connection between the connecting - rings; Fig. 4, a plan view of a portion of Fig. 3, showing a side view of said forked rod; Fig. 5, an edge view of a lever and its mountings, adapted to op- 50 erate said rods; and Fig. 6, a detail side view of a forked rod.

In the manipulation of gates delivering water to a wheel of the turbine or any other suitable variety it is desirable to operate said gates from each end thereof simultaneously, especially if the wheel proper requires a gate-opening of relatively wide breast dimensions, wherein the pressure of the entering water is liable to exert a twisting and binding action upon said gates.

60 By my improvements I aim to operate the gates at each end thereof simultaneously by means of connecting-rings for each end of said gates, a cross connection for said connecting-rings, and suitable operating mechanism acting through said cross connection to actuate the gates; also, to diminish the power required to operate said gates by a screw and lever mechanism.

65 Referring to the accompanying drawings, the letter A designates the casing of a water-wheel, provided with a suitable inlet-opening B, discharge - openings or draft - tubes C C, preferably connected to each side of said casing to deliver the water therefrom, and 70 suitable stuffing - boxes D on said draft-tubes, adapted to form bearings for a shaft E, on which is mounted the wheel proper F, of any convenient style. On the inner ends of said draft-tubes are preferably supported 75 the side plates G, on which are mounted connecting-rings H, by the rollers I, secured to said side plates or otherwise. Each end of each oscillating gate J is provided with an arm connected by a link K to the connecting- 80 ring at that end of the gate. These connecting-rings may be otherwise mounted and otherwise connected to said gates, if so desired. In order to operate both rings simultaneously, 85 and thereby the gates to which they are attached, a cross connection for said rings is provided either in the form of columns L, bolted or otherwise connected to said ring, to one of which columns is conveniently secured an operating-rod M, by means of the usual 90 strap and bolt, or otherwise, said rod leading outside of the case through a suitable stuffing-box and bearing O to be reciprocated by suitable mechanism, such as a hand-wheel P, mounted in a collar Q, supported on said cas- 95 ing by a stand R, or otherwise, and having a screw-threaded connection to said rod, where-

2
by the rotation of said hand-wheel will reciprocate said rod and actuate said gates by the rotation of the connecting-rings. One or more of these rods M may be employed, and I have indicated by dotted lines in Fig. 2 a modification of said rod, which is adapted also to form the cross connection between the rings H' in place of the columns L. Its branches are rigid for this purpose.

10 In Figs. 3 to 6 I have illustrated a forked rod and means for operating said rod, as well as an arrangement of a pair of said rods at substantially diametrically-opposite points on said rings. It will be seen that the columns 15 L are replaced by the branches of the forked rod, which actuate both rings simultaneously, as in the previous arrangement shown in Figs. 1 and 2. The shanks of said forked rods are adapted to be engaged with a lever 20 S, mounted in a bracket T, preferably upon the outside of the casing, said lever being connected by a screw-threaded portion to a screw-threaded rod U, rotated by a hand-wheel V and mounted in a bracket W by means of a 25 collar a on said rod U, or otherwise.

It will be seen that the rotation of the hand-wheel B will oscillate the lever S and reciprocate the rods M in opposite directions and thereby rotate, through the diametrical connection therewith, the rings H and gates connected thereto. The length of the lever S and the connection of the rods thereto at suitable distances from the fulcrum will multiply the power exerted at the hand-wheel V 30 through the screw-threaded rod U. Thus it will be seen that the rings operatively connecting the gates may be rotated from substantially diametrically-opposite points through a suitable cross-connection operated by a mechanism adapted to multiply the power in its 35 transmission to said rings, allowing the manipulation of said gates to be easily effected. Thus it will also be observed that the gates are operated from practically midway their 40 length—that is to say, the operating rod or rods are centrally located with respect to the length of the gates or the distance between the operating-rings—whereby the force applied to operate the gates is free of any tendency to twist 45 or distort the structure to which the gates are pivoted and to twist or distort the gates themselves. It is true that while in Figs. 1 and 2 the operating-rod connects with the cross-columns in the central position, and the operating- 50 rod or rods in Figs. 3 and 4 connect with the operating-rings at points close to the rings, still, nevertheless, that part of the rod or rods to which the operating force is applied is centrally located with respect to the length of the gates or distance between the operating-

rings. It is in this application of the operating force to the gates or gate-rings in such central or midway position that this branch of my invention is realized, in connection with the gates, whose ends are connected with 65 intermediate operating devices—that is to say, devices which transmit to the gates the power applied to such centrally-located actuating rod or rods.

I claim—

1. In a water-wheel, the combination, with a wheel proper, a casing having inlet and outlet openings for water, and gates to regulate the delivery of water to said wheel proper, of a rotatable ring at each end of said gates, 75 adapted to operatively connect said ends, cross connections for said rings to operate them simultaneously, rods engaged with said cross connections at substantially opposite diametrical points, and means to operate said rods from outside said casing.

2. In a water-wheel, the combination, with a wheel proper, a casing having inlet and outlet openings for water, and oscillating gates adapted to regulate the water delivered to 85 said wheel proper, of a rotatable ring at each end of said gates, link mechanism between said rings and said gates, respectively, a pair of forked rods engaged with said rings at substantially opposite diametrical points and interconnecting the said rings in order to operate the same simultaneously, and a lever mechanism engaging with said rods, adapted to operate them in opposite directions and rotate said rings.

3. In a water-wheel, the combination, with a wheel proper, a casing having an inlet-opening for water, draft-tubes to discharge the water from said casing, a wheel proper mounted in said casing, side plates mounted 100 on said draft-tubes and at a relatively wide distance apart, and oscillating gates of corresponding dimensions pivotally mounted between said plates, of a ring mounted at each end of said gates, operative connections between said gates and said rings, respectively, forked rods forming the cross connections between said rings at substantially opposite diametrical points, a lever engaged with the said rods, adapted to operate them in opposite directions, a rotatable rod having a screw-threaded engagement with said lever, and a hand-wheel on said rotatable rod, to operate said lever and rotate said rings.

In testimony whereof I affix my signature in 115 presence of two witnesses.

FRANCIS M. BOOKWALTER.
